[57] CLAIM

The ornamental design for a cable support rack, as shown and described.

DESCRIPTION

FIG. 1 is a perspective view of a cable support rack showing my new design;

FIG. 2 is a side elevation view thereof; and

FIG. 3 is a bottom plan view thereof.

The back of the present cable support rack is flat for contact with and attachment to a wall.

FIG. 1

FIG. 2

FIG. 3
